UNITED STATES PATENT OFFICE.

ALEXANDER EKLUND, OF ATTLEBORO, MASSACHUSETTS, ASSIGNOR TO BLISS BROS. CO.,
OF ATTLEBORO, MASSACHUSETTS.

BRACELET.

1,279,852.

Specification of Letters Patent. Patented Sept. 24, 1918.

Application filed April 11, 1918. Serial No. 227,844.

To all whom it may concern:

Be it known that I, ALEXANDER EKLUND, a citizen of the United States, residing at Attleboro, in the county of Bristol and State 5 of Massachusetts, have invented a new and useful Improvement in Bracelets, of which the following is a specification.

This invention relates to certain new and useful improvements in a bracelet and particularly to a wrist watch bracelet, and it resides in a wrist encircling band formed with a pair of channeled strips which are coiled one upon the other in interlocking relation to permit of limited expansion and 15 ready flexibility.

The invention further resides in the features of construction hereinafter described and claimed, reference being had to the accompanying drawing wherein—

20 Figure 1 is an edge elevation of the improved bracelet, illustrating in dotted lines a watch frame to which the ends of the bracelet are hooked.

Fig. 2 is a plan view of one end portion 25 of the bracelet in its normally contracted form.

Fig. 3 is a similar view showing the coils under tension, being extended to their limit.

Fig. 4 is a fragmentary longitudinal section of the bracelet, and

Fig. 5 is a transverse section on line 5—5 of Fig. 3.

Referring more in detail to the drawing, the bracelet is composed of two strips 1 and 25 2 that are coiled one about the other, each strip being channeled or U-sectioned and thereby forming marginal parallel flanges or projections 3. The inner coiled strip 2 is wound with its marginal flanges on the 40 outside, or so as to extend outwardly, while the outer strip 1 is wound with its flanges 3 within the coils, or so as to project inwardly. The coils of the outer member are staggered relative to those of the inner member, each outer coil being arranged over the 45 abutting edges of two adjacent inner coils so that its inwardly extending flanges 3 will enter channels of the two inner coils and interlock therewith. Either set of coils will, 50 therefore, have its degree of elasticity or stretching limited by the flanges of one

coiled member engaging the flanges of the encircling coiled member.

By having the outer coiled member wound so that its flanges are interiorly disposed, 55 the outside surface is left smooth so as to afford comfort to the wearer.

The coils are flat so as to produce a band-like appearance and to lie flat on the wrist. These flattened coils also restrict the flexibility edgewise of the band while the flexibility broadwise is increased to more 60 easily conform to the wrist.

Attaching hooks 4 have their shank portions inserted in the ends of the coiled members and soldered or otherwise secured thereto, said hooks providing a means for detachably connecting either end to a watch frame 5.

In applying the bracelet, the flat band-like body is passed about the wrist and hooked to the watch frame or case. The smooth exterior of the band does not scratch or injure the wearer. The band readily expands or extends and contracts without presenting any cracks or open spaces to offset its otherwise neat appearance.

Having thus described my invention, what I claim as new and desire to secure by Letters Patent is—

1. A bracelet band composed of flat elongated coils formed by the winding of a pair of flat channel strips one upon the other with the inwardly projecting side flanges of each outer coil straddling the joint between 85 two adjacent inner coils and engaging in their channels on opposite sides of their abutting flanges to interlock therewith and thereby limit the extension of the band during its flexing movements, and an attaching hook inserted in each opened end of the band and formed with a flat bill extending back over and in proximity to the flat band.

2. A bracelet including a flat band composed of a pair of flat strips wound into 95 close flat coils one upon the other, the inner coiled strip having outwardly extending edge flanges and the outer coiled strip overlapping the joints of the inner coil and having inwardly extending edge flanges inter- 100 engaging in but not entirely filling the spaces between the edge flanges of the inner

coil to thereby define a limit to the elasticity of the band, said flat coils providing for greater flexibility sidewise than edgewise whereby the band will readily conform to the wrist, and fastening members on the ends of the band for detachable connection with a watch holder or the like.

In testimony whereof I have signed my name to this specification in the presence of two subscribing witnesses.

ALEXANDER EKLUND.
